Primary Examiner — Omeed Agilee(74) *Attorney, Agent, or Firm* — Jones Walker LLP(57) **CLAIM**

I claim the ornamental design for a resealable vial, as shown and described.

DESCRIPTION

FIG. 1 is a perspective view of a resealable vial showing my new design;

FIG. 2 is a bottom view thereof;

FIG. 3 is a top view thereof;

FIG. 4 is a front view thereof;

FIG. 5 is a back view thereof;

FIG. 6 is a side view thereof; and,

FIG. 7 is a cross-sectional view thereof taken along lines 7-7 of FIG. 2.
